PACKAGING MACHINE FOR ERECTING, FILLING AND SEALING PAPERBOARD CONTAINERS

Clifford G. Cain and Guy B. Le Gendre, Shreveport, La.,
assignors to The Hica Corporation, Shreveport, La., a
corporation of Oregon

Filed Feb. 24, 1965, Ser. No. 83,954

Term of patent 14 years

(Cl. D55—1)

FIG. 3

FIG. 4

FIG. 1 is a perspective view showing the new design for our packaging machine for erecting, filling and sealing paperboard containers.

FIG. 2 is a reduced top view thereof,

FIG. 3 is a perspective view thereof from the opposite side of FIG. 1, and

FIG. 4 is a top plan view with the canopy removed.
We claim:

The ornamental design for a packaging machine for erecting, filling and sealing paperboard containers, as shown.
